DESIGN FOR A BRACELET

William A. McHale, Glen Rock, N. J., assignor to Gemex Company, Union, N. J., a corporation of New Jersey

Application August 24, 1944, Serial No. 115,006

Term of patent 14 years

(Cl. D45—4)

To all whom it may concern:

Be it known that I, William A. McHale, a citizen of the United States and a resident of Glen Rock, in the county of Bergen, State of New Jersey, have invented a new, original, and ornamental Design for a Bracelet, of which the following is a specification, reference being had to the accompanying drawing, forming a part thereof.

In the drawing:

I claim:

The ornamental design for a bracelet, as shown.

WILLIAM A. McHALE.
